UNITED STATES PATENT OFFICE.

C. F. THEODOR STEINWAY, OF NEW YORK, N. Y.

SCREW-CLAMP FOR WOOD-BENDING MACHINES.

SPECIFICATION forming part of Letters Patent No. 229,198, dated June 22, 1880.

Application filed March 10, 1880. (No model.)

To all whom it may concern:

Be it known that I, C. F. THEODOR STEINWAY, of the city and State of New York, have invented certain Improvements in Screw-
5 Clamps for Wood-Bending Apparatus, of which the following is a specification.

My improvements relate to that class of wood-bending apparatus in which screw-clamps are used to hold an object against the
10 curved face of a former or templet; and my invention consists, broadly, in the employment of links, preferably constructed of flat bar-iron, for connecting the clamp-pins, which are inserted transversely through the templet
15 or former, respectively, with the bars through which the clamp-screws are inserted.

One important object of my improvements is to facilitate the bending of the rims of piano-frames upon a short radius, and I have therefore devised links of tapering form, the narrower ends of which are hooked on the pins which pass transversely through the templet, while the larger ends embrace the screw-clamp
20 bar.

25 Heretofore clamps of this character have been made principally of wood, and the necessary size of the wooden links connecting the screw-clamp bar with the former has been such as to prevent the clamps from being placed sufficiently near together to act conjunctively upon a short curve. By my invention, owing to the tapering of the links, I am enabled to set the clamps closer together, and hence to employ a greater number of clamps for holding a plank
30 or rim bent upon a short radius.

That part of my invention which resides in the tapering links may be carried out by giving an inwardly-tapering form to the object, whatever it may be, which connects the screw-
35 clamp bars with the templet, whether such object be in the form of a link, or whether it be a solid bar, perforated or otherwise, so constructed as to admit of connection with the clamp-bar and templet.

40 It will, of course, be seen that in either event the tapering of this instrumentality will permit the clamps to be set close together upon a comparatively short curve.

In the accompanying drawings, representing
45 my invention, Figure 1 is a top view of a former or templet provided with my improved

taper-link clamps. Fig. 2 is a transverse section of the former and one of the clamps through the line *x x* on Fig. 1. Fig. 3 is a transverse section of the screw-clamp bar through the line *y y* on Fig. 2. Fig. 4 is a transverse section of a screw-clamp bar composed of two metallic tubes, one inside the other, Figs. 3 and 4 being drawn on an enlarged scale for clearness of illustration.

55 In the drawings, a templet or former, A, of the shape required for forming the rim of a piano-frame, is, it will be seen, provided with a series of transverse holes, *a*, for the reception of the clamp-pins B. Each of these pins, 60 it will be observed, projects sufficiently from the surface of the templet to be embraced by the smaller end *c* of one of the tapering links C, the larger end *c'* of which embraces the screw-clamp bar D, through which the clamp- 65 screws *d* are transversely inserted. The clamp, therefore, considered by itself, consists of a screw-clamp bar, D, and a clamp-pin, B, linked together by the two tapering links C C, which, 70 in operation, are applied one on one side and 75 the other on the other side of the templet or former.

I use, preferably, iron tubes for both the pins and the screw-clamp bar, and tightly fill the interior of these tubes with hard wood. 80

I may also use in the construction of the screw-clamp bar two tubes, or a nest of tubes, one inside the other, as shown in Fig. 4; but I have found that for ordinary purposes sufficient rigidity is obtained by the employment 85 of a single metallic tube filled with hard wood; and a part of my invention consists in a screw-clamp bar composed of a metallic tube completely filled with wood.

90 For the purpose of thus filling the tube, I turn a cylinder of wood to fit the interior of the tube, and then cut out a longitudinal section of the cylinder, and having inserted the two segments in the iron tube, I then drive between them a tongue of wood slightly thicker 95 than the section which has been removed, as shown in Fig. 3, in which the two wooden segments E E' are represented as being tightly held in the tube by the interposed tongue F, which has been driven in between them.

100 My clamp-screws *d* have the usual square threads, and are inserted transversely through

the clamp-bar D, and are engaged by female threads formed in the saddle g, which is permanently secured to the clamp-bar D by means of the screws g'. The sides g² of the saddle 5 converge toward the former, and the bearing of the links upon these converging sides prevents the lateral tilting of the clamp, and preserves the proper alignment of the clamp-screws with the center of the pin inserted 10 through the former.

I employ in connection with my clamps a shield, H, which receives the impact of the clamp-screws and transmits their thrust to the plank or rim I, which is interposed between 15 the shield and the periphery of the former while undergoing the process of bending.

I preferably build up my former or templet of several layers of planks glued together, with the grain of the wood of the several layers arranged in relatively different directions, 20 and I may surround the periphery of the former with the iron plate A'.

Iron ferrules a' may, if desired, be inserted in the holes a for the reception of the clamp-pins B. This, however, will not be necessary 25 except for adapting the apparatus for bending very thick planks.

In operation, my clamps are readily applied by hooking the smaller end of the links over 30 the two projecting ends of the clamp-pins and the larger ends of the links over the opposite ends of the clamp-bars, and then turning the

clamp-screws against the shield, which bears upon the exterior surface of the object which is being bent. When the bending operation 35 is completed the object operated upon is easily detached by turning back the clamp-screws and removing one set of links.

I claim as my invention in apparatus for bending wood—

1. A detachable clamping device for application to a former, the said device consisting of two metallic bars and two removable tapering metallic links for respectively connecting the opposite ends of the bars with each other, 45 a screw bolt or bolts inserted transversely through one of the bars, and a shield for receiving the impact of the screw or screws and transmitting the thrust of the same to an object interposed between the shield and the periphery of a former in or upon which the other bar of the clamping device is sustained, substantially as set forth.

2. The saddle g, affixed to the clamp-bar D, and presenting upon its sides, near the end of the clamp-bar, two relatively-inclined surfaces, in combination with the tapering metallic link C, the sides of which are afforded bearings upon the said relatively-inclined surfaces, substantially as and for the purpose set forth.

C. F. THEODOR STEINWAY.
